UNITED STATES PATENT OFFICE

LINUS D. HOUSER, OF WINCHESTER, CALIFORNIA

CURTAIN ROD THREADER

Application filed October 17, 1931. Serial No. 569,487.

This invention relates to curtain rod threaders, and more particularly to a threader which is adapted for use with either round or flat curtain rods.

- 5 An object of this invention is to provide a threader or cap which is adapted to clamp onto one end of a curtain rod so as to facilitate the sliding of the rod through the hem of the curtain.
- 10 Another object of this invention is to provide a device of this kind which is so formed that it will tightly clamp onto either a round or flat curtain rod and protect the hem of the curtain from the end of the rod as the rod is being pushed therethrough.

15 The above and various other objects and advantages of this invention will in part be described in and in part be understood from the following detailed description of the 20 present preferred embodiment, the same being illustrated in the accompanying drawing, wherein:—

25 Figure 1 is a detail side elevation of a device constructed according to the preferred embodiment of this invention, having a round curtain rod mounted therein;

Figure 2 is a sectional view taken on the line 2—2 of Figure 1;

30 Figure 3 is a detail side elevation partly broken away of the device, having a flat curtain rod mounted therein, and

Figure 4 is a sectional view taken on the line 4—4 of Figure 1.

35 Referring to the drawing wherein like numerals of reference designate corresponding parts throughout the several views, the numeral 10 designates generally a round curtain rod, and the numeral 11 designates a cap or threading member which is removably positioned on one end of the rod 10, this threadder 11 comprising a body of substantially cylindrical configuration which is split longitudinally at diametrically opposed 40 points, as at 13, the split portion extending

from the inner end to a point adjacent the closed end portion 12 of the threadder 11.

The threadder 11 is also provided with laterally projecting portions 14 at diametrically opposed sides, these projecting portions 14 being adapted to removably receive the opposite edges of a flat curtain rod 15. The round portion 11 projects forwardly from the offset portions 14 so as to provide a head or forwardly projecting member for 55 initially opening up the hem within which the curtain rods 10 or 15 are being placed.

Through the use of the split portions 13, a threading member of resilient construction is provided which will readily fit curtain rods 60 either round or flat, which are of different sizes, but where the sizes vary only slightly one from another.

In the use of this device, the threading member 11 is adapted to be slipped over one 65 end of the curtain rod of either round or flat cross sectional configuration and the rod with the threadder mounted thereon then slipped into the hem of the curtain. As the rod is being forced into the hem, the threading member 11 will open up the hem and due to the blunt end portion thereof, the threading member 11 will not tear or otherwise injure the curtain.

70 It will be noted that the threading member herein disclosed may be readily stamped or formed from a single piece of metal of desired inherent resiliency, and due to the configuration of the device, it can be used 75 for curtain rods, which are either flat or round in cross section.

80 It is, of course, understood that various changes and modifications may be made in the details of construction and design of the 85 above specifically described embodiment of this invention without departing from the spirit thereof, such changes and modifications being restricted only by the scope of 90 the following claim.

What is claimed is:—

A curtain rod threader for round or flat rods, comprising a cylindrical body open at one end, a blunt member formed with the 5 opposite end, said body being split longitudinally at diametrically opposed points, and a pair of opposed longitudinally extending offset portions formed with the body, said offset portions being arcuate in transverse section and having a radius less than the radius of the body.

10 In testimony whereof I hereunto affix my signature.

LINUS D. HOUSER.
